IMPROVEMENT IN DEVICE FOR DETACHING HORSES FROM VEHICLES.

B. A. McCONNAUGHEY, OF NEW MARKET, OHIO.

Letters Patent No. 60,533, dated December 18, 1866.

The Schedule referred to in these Letters Patent and making part of the same.

TO ALL WHOM IT MAY CONCERN:

Be it known that I, B. A. McCONNAUGHEY, of New Market, in the county of Highland, and State of Ohio, have invented certain new and useful Devices for Detaching Horses from Vehicles; and I do hereby declare that the following is a full, clear, and exact description thereof, reference being had to the accompanying drawings, and the letters of reference marked thereon, making a part of this specification.

In the annexed drawings A A represents an ordinary pair of vehicle shafts, to which is attached a single-tree, B. Passing around the bottom, and bent up at each end of said single-tree, is a metallic bar, *m*, which bar has an opening, *x*, made at each end. *b b* represent two springs placed upon the upper surface of the single-tree and pivoted (as seen at *z z*) thereto. The outer ends of the said springs are so constructed as to pass into the openings, *x*, of the bar, *m*, while the inner ends, which extend to near the centre of the single-tree, are slightly elevated. Directly under the raised portions of the springs, *b b*, is secured a curved spring, *d*, the construction of which is somewhat similar to that of a common vehicle spring. *a* represents a lever, (having suitable supports,) which extends to the rear of the single-tree, and is provided with two prongs, by which means it is connected to the inner ends of the springs, *b b*. D D are wooden or metallic tugs, which are attached in any ordinary way to the ends of the traces, C C. These tugs are provided with a small groove, and are cut out slightly in their centres, so that shoulders are formed on the upper side. (See Figure 2.) These tugs fit snugly within the opening formed at the ends of the single-tree by the bar, *m*, and are there tightly held by the ends of the springs, *b b*, which lie within the openings heretofore described, and secured to the shoulders there formed. By elevating the end of the lever, *a*, the inner ends of the springs are forced down, throwing the outer ends of said springs upwards, and allowing the tugs, D D, to pass from under without hindrance. In the ordinary usage of my invention, a strap is connected to the end of lever *a*, and extends over the dash-board of the vehicle, so that in case of the animal's "running off" he can be allowed to pass from the vehicle without danger to the occupants thereof.

I do not claim the springs *b b*, with under spring *d*, but what I do claim is, the tugs D D, connected to the end of the traces and fitting within the openings therefor provided, and held by the bar *m*, when used in combination with the springs and lever *a* for detaching the horse, substantially as herein set forth.

As evidence that I claim the foregoing, I have hereunto set my hand in the presence of two witnesses.

B. A. McCONNAUGHEY.
